UNITED STATES PATENT OFFICE.

JOHN FRANKLIN SCRIBNER, OF CHICAGO, ILLINOIS.

NON-GLARE REFLECTOR.

Specification of Letters Patent. Patented June 22, 1915.

1,143,650.

Application filed March 13, 1915. Serial No. 14,076.

To all whom it may concern:

Be it known that I, JAMES FRANKLIN SCRIBNER, a citizen of the United States, residing in the city of Chicago, county of Cook, and State of Illinois, have invented 5 certain new and useful Improvements in Non-Glare Reflectors, of which the following is a specification.

My invention relates to reflectors and has 10 more particular reference to reflectors for lamps such as automobile headlights and the like.

The glare from the high power lamps 15 with which automobiles are equipped at the present time has proven exceedingly objectionable in city streets and has given rise to legislation in many cities requiring the use of dimming devices to prevent the blinding effect of such intense lights upon pedes- 20 trians and the drivers of other cars. Such dimming devices have in many instances proven effective to deaden and obstruct the driving light as results in notable disad- 25 vantage to the driver of the car.

The principal object of the present invention is to provide a lamp and specifically a reflector for a lamp which does not produce the objectionable glare complained of 30 and which will at the same time be effective to provide strong driving light when in use with lamps of the ordinary power.

Another object is to provide a reflector 35 in the nature of an attachment which may be secured to lamps now in use whereby the desired advantages may be had without the expense of a new lamp or any alteration in the lighting system other than to apply the reflector.

Another object is to provide a reflector of 40 simple construction, small cost, light weight, and also one of a metal having peculiarly advantageous properties for the uses pointed out, and which properties and advantages 45 for this purpose I claim to have discovered by experiment and study.

Other objects and advantages will appear hereinafter.

In the accompanying drawings, which 50 form a part of this specification I have illustrated preferred and modified embodiments of these improvements in their application to lamps of well known types respectively.

In these drawings Figure 1 is a medial 55 vertical section through a conventional form of electric lamp with the preferred form of

my improved reflector, as an attachment, thereon; Fig. 2 is a medial vertical section through a gas lamp having the preferred form of these improvements for such use 60 thereon, some of the parts being shown in full lines; Fig. 3 is a fragmentary sectional view similar to that of Fig. 1 in which the silvered reflector of the lamp is modified, and showing an attachment to overcome 65 glare; Fig. 4 is a medial vertical section of the reflector attachment, as in Fig. 1, on a reduced scale, showing also a method of modifying its reflecting surface; Fig. 5 is a similar view to that of Fig. 4 showing a 70 method of providing a modified form of surfacing for the reflector; Fig. 6 is a front or face view of the reflector of Fig. 4 in its completed state; and Figs. 7 and 8 are fragmentary front views showing other modifications of the surfacing or finish of reflect- 75 ing surfaces.

My improved reflector 10, 10^a is preferably concavo-convex and may be of any of the well known general forms now in 80 use. For gas lamps, as in Fig. 2, it is preferably more shallow than in the electric lamps, owing to general features of construction of gas lamps. For electric lamps it may well be of the general parabolic 85 shape, and when employed as an attachment for such lamps, as in Fig. 1, it preferably conforms to the general interior surface of the fixed reflector 11 in the lamp. The central portion 12, however, is preferably flat- 90 tened, that is, formed substantially at right angles to the axis of the reflector, substantially as illustrated. This central portion 12 has preferably a high reflecting power, which means that it is highly polished if of 95 metal, or silvered if of glass, or given such high power of reflection by ways well understood in the art according to the material employed. An opening 13 surrounded by the annular flange 14 is adapted to accommodate the socket element 15 of the lamp 16, which socket element and lamp are well known in the art.

A principal point of departure from the heretofore known is with respect to the annular area or surface about the central portion 12. This annular surface 17 is preferably first given a relatively high finish or reflecting power similar to that of the portion 12. That is to say, the entire interior 110 or reflecting surface of the reflector is first given such polish or finish. After such pol-

ishing or finishing the entire interior surface with the exception of that of the portion 12 is cut, etched, chased or scratched so as to break up this polished surface into 5 a multitude of relatively small polished surfaces defined by the scratch-like cuts.

In Fig. 4 I show one means of scratching or cutting this reflecting surface, these means comprising a rotary steel wire brush 10 19 driven by any approved means, the polished surface 17 of the reflector being passed in contact with the brush say from the outer edge 18 thereof inward to the portion 12, scratching the reflector with substantially 15 parallel cuts or lines of abrasion and making a path of such cuts, say about one-half or five-eights of an inch wide. This operation is repeated until such paths of lines of abraded or cut surface are made side by 20 side, over the entire reflecting surface 17.

In Fig. 5 I have shown an axially rotating steel brush 19 with the ends of the steel wires thereof in contact with the polished surface 17, the brush thus producing substantially 25 circular scratches. When the reflector is passed in contact with this brush 19 in the manner described, a path of interwoven spiral cuts or scratches is formed, and by repeating the operation the entire 30 surface is scratched in paths leading from the outer edge to the portion 12. In both instances I prefer to pass the reflector so rapidly across the brush that although the scratches are manifold there are intervening 35 bright surfaces between them, that is, surfaces unscratched, which are, however, relatively small. The invention is not limited to the exact manner of cutting or scratching the polished surface, and I conceive that advantageous 40 results would be obtained by forming these scratch lines parallel to each other and circularly about the axis of the reflector, as in Fig. 7, or by crossing them as in Fig. 8, or otherwise breaking up the polished surface into relatively small surfaces 45 defined by such cuts. An important advantage of the scratching or cutting resides in the fact that the irregularity thus produced in the general surface 17 gives rise to 50 reflections of light from the scratches themselves, these scratches being clearly discernible at a distance of say forty feet or more from the lamp when it is normally in use. From in front of the lamp the 55 scratches glow with light.

When a lamp equipped with my present reflector is normally in use with a lamp of such power that with the ordinary silvered reflector the glare would be practically blinding, it is possible for a person to look 60 directly into the lamp at any distance and from any angle without the slightest inconvenience to his eyes. Viewed directly from in front with the eyes of the person 65 on a horizontal plane with the light he sees

a small spot of bright light in the very center, which is the film of the bulb. He also sees a very narrow circular ring of light about the central spot, which is a reflection of light from the bulb. The portion 12 of the reflector appears relatively dark. Surrounding this portion 12 there is an illuminated field which is of a silvery white cast in my present devices, which field glows with brightness. No glare comes from this portion whatsoever, and I have not found that any glare emanates from any portion of the lamp with my reflector in place. The glowing film appears merely as a spot of light and can be gazed upon freely without inconvenience. From the driver's seat the illumination is ample or even more than sufficient for ordinary purposes. In the case of a motor ladder truck in the fire department of the city of Chicago, an auxiliary 85 hand-operated search light has been dispensed with as unnecessary since my reflectors have been installed in the head lights thereof. The light emanating from the lamps is diffused and distributed equally in a wide path in front of the machine.

The reflectors which I am employing as attachments for lamps already installed, as in Figs. 1 and 2, are preferably made of aluminum, this metal being at once light 95 and susceptible of high polish. I conceive that I have made a valuable discovery or invention in the employment of aluminum for this purpose, the color of this metal and its property of retaining a high polish for 100 a long period peculiarly adapted it to this use.

I have treated silvered reflectors by my scratching process with quite advantageous results; but it is pointed out that in so treating the parabolic silvered reflector the central bright portion 12^a, Fig. 3, will produce a very objectionable glare, and the best results will not be obtained. To overcome this 105 aluminum or other material may be inserted, as in Fig. 3.

In the device of Fig. 1 my reflector may be attached by merely detaching the bulb 16, inserting the reflector and reattaching the bulb, the glass 22 holding the reflector in place. Ordinarily, however, the reflector fits tightly enough upon the lamp socket 15 to be held thereby. In the gas lamp of Fig. 2 the reflector 10^a may be secured by merely 110 removing the nuts 25, removing the old reflector, and inserting the one illustrated.

The highly polished portion 12 is important from the standpoint of driving light, such light being materially reduced when 115 this surface is also scratched. The illustrated arrangement of the surface 12 and its freedom from scratch-like marks are considered by me the most advantageous ways for practising the invention in these regards. 130

The reflectors, when of aluminum or other ductile metal may be spun into the desired shape or otherwise formed according to practices well understood in the mechanic arts.

5 While I have illustrated and described preferred and modified embodiments of these improvements, the invention is not limited to the exact construction or manner 10 of roughening or scratching the reflecting surface, and all departures therefrom as fall within the scope of the appended claims are considered by me to be within the spirit of the invention set forth.

15 I claim:

1. A reflector adapted to be positioned adjacent to a source of light to reflect rays thereof and having a reflecting area comprising a substantially flat central portion 20 adapted to be positioned directly adjacent to the source of light and of relatively high reflecting power, said reflector having about said substantially central portion an annular portion of relatively low reflecting power.

2. A reflector adapted to be positioned adjacent to a source of light to reflect rays thereof and having a reflecting surface concave in form, the substantially central area of said reflector being substantially flat and 30 having relatively high reflecting power, said reflector having about said central area an annular area having a surface of relatively low reflecting power.

3. A reflector adapted to be positioned adjacent to a source of light to reflect rays thereof and having a reflecting area concave in form, the substantially central portion of said reflector having a flattened reflecting surface of relatively high reflecting 40 power, said reflector having about said central portion an annular portion having a surface containing scratch-like cuts close to each other and thereby roughening said annular surface to decrease its reflecting power.

4. A reflector adapted to be positioned adjacent to a source of light to reflect rays thereof and having a reflecting surface comprising a substantially central area thereof 50 adapted to be positioned directly in line with the source of light and of relatively high reflecting power, said reflector having about said substantially central area an annular area having a substantially smooth 55 general surface containing scratch-like cuts therein close to each other and breaking up the general surface of said annular area into relatively small reflecting surfaces defined by said scratch-like cuts.

60 5. A concave reflector having a reflecting surface of aluminum and adapted to be positioned adjacent to a source of light to re-

flect rays thereof, the substantially central portion of said reflecting surface being polished, the annular portion of said reflecting surface about said central portion being provided with fine scratch-like cuts shallow and close to each other whereby such annular surface is provided with small reflecting surfaces constituting the walls of 70 such cuts.

6. A concave reflector having a reflecting surface of aluminum and adapted to be positioned adjacent to a source of light to reflect rays thereof, the substantially central 75 portion of said reflecting surface being substantially flat and polished, the annular portion of said reflecting surface about said central portion being abraded or roughened.

7. In combination, a lamp casing, a source 80 of light within said casing and a reflector behind said source of light when viewed from the front, said reflector having a substantially flat surface of high reflecting power immediately back of said source of 85 light and an annular reflecting surface about said central surface provided with scratch-like cuts close to each other and providing relatively small areas of high reflecting power defined by such scratch-like cuts. 90

8. A reflector of concavo-convex shape having an opening in the central portion thereof, said reflector having a surface of high reflecting power about said opening and having a surface about said central surface broken by scratch-like 95 cuts relatively close together.

9. A reflector of concavo-convex shape having an opening in the central portion thereof, said reflector having a substantially 100 flat surface of high reflecting power about said opening and having a surface about said central surface broken by scratch-like cuts relatively close together.

10. As an attachment for a lamp which 105 has a substantially parabolic reflector and a source of light substantially at the focus thereof, a reflector adapted substantially to fit upon said other reflector throughout a substantially large portion thereof, the reflecting surface of said attachment reflector having a relatively large area thereof provided with scratch-like cuts substantially close to each other and providing a multitude of intervening surfaces of relatively high reflecting power, the portion of said attachment adapted to be positioned immediately 110 behind the source of light being substantially flattened.

Correction in Letters Patent No. 1,143,650.

It is hereby certified that in Letters Patent No. 1,143,650, granted June 22, 1915, for an improvement in "Non-Glare Reflectors," in the grant and in the heading to the printed specification the name of the patentee is erroneously written and printed "John Franklin Scribner," whereas said name should have been written and printed as *James Franklin Scribner*; and that the said Letters Patent should be read with this correction therein that the same may conform to the record of the case in the Patent Office.

Signed and sealed this 6th day of June, A. D., 1916.

[SEAL.]

J. T. NEWTON,

Acting Commissioner of Patents.
